LAMP WRENCH

Marcel E. Demyttenaere and James E. Peys,
West Springfield, Mass.

Application April 23, 1935, Serial No. 17,823

6 Claims. (Cl. 294—20)

Our invention relates to improvements in lamp wrenches.

An object of our invention is to provide a lamp wrench, or tool, for removing and replacing electric lamp bulbs which may be located at a height, or position, ordinarily inaccessible from the floor, without the use of a ladder.

A further object of our invention is to provide, in such a device, means for automatically gripping and releasing the lamp, as the device is pushed toward, or pulled away from, a socket in which the lamp is engaged.

A still further object of our invention is to provide a lamp wrench having a plurality of gripping fingers and means for inducing co-operation between the gripping fingers, so that they operate in unison, both in the opening and closing operations.

Another object of our invention is to provide, in co-operation with the lamp wrench or tool, means for gripping or holding a fixture or socket, in which the lamp may be attached or connected, as with a thread, while removing the lamp from the fixture or socket, in order to prevent revolution of the fixture, while the lamp is being screwed into, or unscrewed from, the socket.

These, and other objects and advantages of our invention, will be more completely described and disclosed in the specification, the accompanying drawings, and the appended claims.

Broadly, our invention comprises a handle or pole member, a plurality of adjustable bearing arms secured on the pole, lamp-gripping or finger members, pivotally secured on the bearing arms, spring means for normally holding the lamp-gripping members in open position, a tube, or sleeve slidably mounted on the pole, clamping members secured on the slideable sleeve for engaging a shade socket or other fixture in which a lamp may be located, and co-operating means on the pole and the sleeve for operating the clamping members to engage or disengage a lamp fixture or socket.

A preferred embodiment of our invention is illustrated in the accompanying drawings, in which:

Fig. 1 is a partial elevational view of our device, with the various elements thereof in open or disengaged relationship.

Fig. 2 is a detail view, illustrating the operation of one of the lamp-gripping or engaging fingers.

Fig. 3 is a view, similar to Fig. 1, showing the various parts in their closed, operative, or lamp-engaging position.

Fig. 4 is a side, elevational view, illustrating the

device gripping a lamp, and in position for disengagement of the fixture clamping members.

Fig. 5 is a vertical, sectional view of an extension for the pole and sleeve.

Fig. 6 is a cross sectional view on the line 6—6 of Fig. 5.

Fig. 7 is a cross sectional view on the line 7—7 of Fig. 3.

Fig. 8 is a cross sectional view on the line 8—8 of Fig. 3, and

Fig. 9 is a plan view, illustrating a modified form of clamping members for gripping a lamp socket.

Referring now to the drawings in detail, in which like numerals refer to like parts throughout:

A tubular handle, or pole member 1, has secured in the upper end thereof, a plurality of bearing arms 2 which are split and formed with clevises 3 at their upper extremities. The arms 2 are formed of a suitable bendable material, and may be bent inwardly, or outwardly, at will, to adjust the device for various sizes of lamps. Lamp-gripping members 4 are pivotally secured at 5 in the clevises 3, and are provided at their upper ends with resilient cap members 6 of rubber, or other suitable material. Each of the lamp-gripping members 4 is connected by means of a U-shaped wire member 7, that is located in an opening 8, provided in the member 4, to a common terminal member 9, which is secured to a tension spring 10. The spring 10 is anchored on a pin 11 that is secured in the pole member 1. The spring 10 exerts a pull on the members 7, which tends normally to revolve the gripping members 4 on their axes 5 into open position, as indicated in Fig. 1, and in full lines in Fig. 2. Stop pins 12, on the members 4, engage the bearing clevises 3 to limit the outward movement of the lamp-gripping members 4, induced by the action of the spring 10.

The members 4 are formed with inwardly, extending finger portions 13 which, in the normal open position converge approximately horizontally toward the axis of the pole 1.

In operation, the pole 1 is raised, or moved, toward a lamp 14. When the lamp 14 impinges against the extension portions 13 of the members 4, these members are revolved about their axes 5, against the tension of the spring 10, until the lamp 14 is firmly gripped by the rubber caps 6 and portions 13, as indicated in dotted lines in Fig. 2, and in Figs 3 and 4. The lamp 14 may then be unscrewed from its socket by rotating or turning the tubular pole 1 about its axis.

A lamp may be inserted in a socket by a reversal of this operation, by inserting a lamp between the members 4, then, screwing into the lamp socket. A downward pull on the pole 1 will then release the lamp-gripping members 4, which are automatically returned to open position by the action of the spring 10. The U-shaped wire members 7 may serve as a stop and support for the lamp 14, as indicated in Figs. 3 and 4.

If the lamp 14 is installed in a hanging fixture, it is difficult, and sometimes impossible, to unscrew the lamp from the fixture without first clamping, or holding, the fixture, as otherwise the fixture will revolve with the lamp, thus preventing its removal. We have provided means for holding a fixture or socket, while a lamp is being removed, or replaced, therein. A tubular member 15 is slidably mounted on the pole 1, and is provided, at its upper end, with a fixed collar 16 to which the clamping arms 17 are secured. These arms are forked at 18, (see Fig. 4), to provide clamping portions 19, which are shaped to conform approximately to the contour of a lamp shade 21 and are provided with resilient jackets 20. The arms 17 are shaped to provide a spring tension, which normally retains the arms 17 in a distended, or open position, as indicated in Fig. 1. They are guided between rollers 22 and 23, which are mounted in a frame 24, which frame 24 is supported on the tubular member 15, by means of a wire frame 25, and ring 25', and moves with the tubular member 15.

In operation, the shade-clamping device is raised into engaging proximity to a lamp shade 21, as shown in Fig. 1, with the pins 11 on the pole member 1, located beneath the slideable frame 24, as shown in Fig. 4. The handle, or pole member 1, is then raised, relative to the tube 15, until engagement of the pins 11 with the under side of frame 24, which operation raises or moves the frame 24 upward, relative to the shade-clamping arms 17, thereby forcing the arms 17 inwardly into engagement with the lamp shade 21, as indicated in Fig. 3. The pole member 1 is then turned axially, until the pins 11 will pass freely between the sides of the frame 24 and further raised, until the pivoted members 4 firmly grip the lamp 14. Rotative movement of the pole member 1 will unscrew the lamp from its socket. With the lamp securely held in between and by the members 4, the member 1 is then pulled downwardly, relative to the tubular member 15, and engagement of the pins 11 on the top of the frame 24, forces the frame 24 downwardly, thus opening the shade-clamping arms 17, returning them to the position shown in Fig. 1, and releasing the lamp shade. The lamp may then be removed from the members 4, and another lamp inserted therein, and the second lamp screwed into the socket by a repetition of the process, above described, except that the pole member 1 will be rotated in an opposite direction, to screw the lamp into the socket. The spring arms 17 are formed with the re-entrant recesses 17', which allow the spring arms to open full width, as shown in Fig. 1.

In Fig. 9, we have illustrated, in plan view, a modified form of clamping members for use with a lamp socket which may not be equipped with a shade, or reflector. The arms 19' are extended inwardly, toward the axis of the pole member 1, until they cross and are secured together at the intersection 25'', thus forming V-shaped clamping portions 26, which will firmly grip a lamp socket 27.

For use in the removal and replacement of lamps installed in rooms with a very high ceiling, such as halls, auditoriums, gynasiums, and industrial plants, we have provided means for extending the pole members 1 and 15. The member 1 is provided, at its lower end, with detents 28. A tubular member 29 has secured, in its upper end, a block 30 which is grooved at 31 to receive a spring strip 32, formed with shoulders 33. When the block 30 is pushed into the member 1, the shoulders 33 engage the detents 28, to hold the members 1 and 29 firmly assembled as a unitary structure, and co-operation between the grooves 31 and detents 28, provides for unitary rotation of the members 1 and 29 for operation of the members 4, and pins 11. A sleeve 34, provided with a collar 35, is slidably mounted on the member 29, and may be engaged on the sleeve 15, by inserting the end of the sleeve 15 in the collar 35, in which it is designed to fit snugly. It is necessary to extend the sleeve 15, as well as the member 1, as it is necessary to hold the arms 17 stationary, during relative movement of the member 1 and frame 24.

What we claim is:—

1. An electric lamp bulb removing device comprising, a rod member, a tubular member in which the rod member is slidably and rotatably mounted, arm members directly connected to the rod member, lamp-gripping members pivotally secured to the arm members, a stop on the lamp-gripping members engaging the arm members, a spring having one end secured to the rod member, U-shaped connecting means between the other end of the spring and the pivotally mounted lamp-gripping members for causing all of the lamp-gripping members to operate in unison when the rod member is actuated in the tubular member to grip a bulb for removing the bulb from its socket, or, for inserting a bulb.

2. In a lamp bulb removing and inserting device, a tubular member, a rod slideable and turnable therein, flexible arms secured to the rod, lamp-gripping members pivotally supported on the said arms, spring-actuated means interposed between the rod and the lamp-gripping members for causing all of the said members to operate in unison when engaged by a lamp bulb, shade-clamping means comprising spring arms secured to the tubular member, a frame device movably mounted on the rod and engaging the spring arms for moving the same into their shade-clamping positions, means on the rod engaging the said frame for moving the same when the rod is turned in one position for moving the spring arms into their shade-clamping position and for disengaging the said frame when the rod is turned into another position for actuating the lamp-gripping means independently of the shade-clamping means.

3. In combination, in a lamp socket clamping device and lamp-gripping device for inserting and removing a lamp, a tubular member, a rod slideable and turnable therein, projections on the rod, spring arms secured to the tubular member for clamping a lamp socket, frame means spaced from the rod engaging the spring arms for moving the said arms into or away from their socket-clamping positions when engaged by the projections on the rod, arm members secured to the rod, lamp-gripping members pivotally secured to the arm members which are actuated when moved against the lamp, and spring means for actuating all lamp-gripping members.

4. In combination, in a lamp socket clamping

device and lamp-gripping device for inserting and removing a lamp, a tubular member, a rod slideable and turnable therein, spring arms secured to the tubular member for clamping a lamp socket, 5 means on the rod for moving the spring arms into or away from their socket-clamping positions, arm members secured to the rod, lamp-gripping members pivotally secured to the arm members which are actuated when moved against 10 the lamp, and spring means for actuating all of the lamp-gripping members, said spring arms having moving means comprising a frame with spaced members between which the rod is located, rollers in the frame between which the spring 15 arms are located, projections on the rod for engaging either the upper or lower edges of the frame depending whether the spring arms are to be moved for clamping or releasing the lamp socket, said projections being movable through 20 the frame when the rod is turned for locating the projections either above or below the frame.

5. A lamp-inserting and removing device comprising a rod, a tubular casing in which the rod is located for rotatable movement for inserting 25 and removing a lamp, bendable members secured to the rod, lamp-gripping members having curved inner surfaces that are pivotally mounted on the

bendable members, a retractile spring secured on the rod with its axis in the axis of the rod, a member pivotally connected to each lamp-gripping member and to the spring for mutually moving all of the lamp-gripping members in unison, 5 said pivotally connected members being located for supporting a lamp bulb when located in the gripping members.

6. A lamp-inserting and removing device comprising a rod, a casing in which the rod is located for rotatable movement, bendable members secured to the rod, lamp-gripping members having curves which are pivotally mounted on the bendable members, a retractile spring secured on the rod with its axis in the axis of the rod, a member 10 pivotally connected to each lamp-gripping member and the spring for mutually moving all of the lamp-gripping members in unison, said pivotally connected members also serving to partially support a lamp bulb when located in the 15 gripping members, means for clamping a lamp socket, and means operable by the rod for moving the lamp socket clamping means when a lamp is to be inserted or removed. 20
